UNITED STATES PATENT OFFICE.

EARL JAMES KIRKER AND THEODORE WILLIAM OLGES, OF COVINGTON, KENTUCKY.

SIGN-PLATE AND METHOD OF MAKING SAME.

1,288,920.

Specification of Letters Patent. Patented Dec. 24, 1918.

Application filed April 20, 1917. Serial No. 163,392.

To all whom it may concern:

Be it known that we, EARL J. KIRKER and THEODORE W. OLGES, citizens of the United States, residing at Covington, in the county 5 of Kenton and State of Kentucky, have jointly invented certain new and useful Improvements in Sign - Plates and Methods of Making Same, of which the following is a specification.

10 Our invention relates to metallic sign-plates and to the method of making the same, and has for its object the provision of a sign which will closely resemble a usual etched sign-plate, but which may be manufactured in large quantities at a fraction of 15 the cost of genuine etched signs.

The invention consists in a novel method of printing portions of the face of a suitable sheet-metal plate, so as to obtain dull un- 20 glazed printed surfaces, and subsequently embossing the sheet-metal plate to form relief portions upon its face intermediate of the printed surfaces, the relief and printed portions of the plate together forming a 25 novel imitation of the non-corroded and corroded portions of a genuine etched sign-plate.

The invention will be readily understood from the following description and claims, 30 and from the drawings, in which latter:

Figure 1 is a plan view of a sign-plate formed in accordance with our invention.

Fig. 2 is an enlarged fragmentary plan view of a corner of the metallic plate from 35 which the sign-plate is formed, after printing the same.

Fig. 3 is a cross-section taken upon the line 3—3 of Fig. 2, the parts being exaggerated for the sake of clearness.

40 Fig. 4 is a vertical cross-section of a simplified apparatus, by means of which the embossing of the metallic plate may be performed.

Fig. 5 is a cross-section similar to Fig. 3 showing the metallic plate as received from the embossing press; and,

Fig. 6 is an enlarged fragmentary longitudinal section of the sign-plate taken upon the line 6—6 of Fig. 1.

50 Our improved sign is exemplified as formed from a sheet-metal plate represented at 11. The sheet-metal plate is preferably formed flat, and is instanced as comprising a backing 12 suitably plated with a facing 13, the surface 14 of which is adapted to form the face of the sign-plate. The facing

13 is preferably of a ductile and tenacious metal such as brass and the backing of the sheet-metal plate is preferably of a less tractable and less ductile metal instanced as zinc. 60

The sheet-metal plate is printed as shown in Figs. 2 and 3, from a printing-plate so designed that the portions of surface 14 which are to imitate the corroded portions of an etched plate, will receive the printed impressions, as shown at 16. The printed impressions are preferably formed with slightly irregular surfaces so as to present a dull, unglazed appearance, forming a striking resemblance to the corroded portions of 70 a genuine etched plate.

For this purpose we employ a printing-ink having a fatty body, such for example, as the inks used in lithographic printing, and add to such ink a binding agent, which 75 may be silicate of soda for example, and which is adapted to cause greater cohesion among the pigments of the ink, and to puff up the pigments into a slightly irregular surface, as shown at 19, when the ink is applied to the metallic surface of the sign-plate.

The use of such printing ink permits the making of the printed impression upon the metallic sign-plate from a usual etched printing-plate without resorting to lithographic 85 printing, the binding agent providing the necessary tack to cause the ink to adhere to the metallic sign-plate, and uniting the pigments for producing sufficient viscosity and stiffness in the ink to prevent the ink 90 being pressed out of the printing lines of the printing-plate, when the latter is forced against the sign-plate with the necessary pressure for making a printed impression upon metal. 95

If desired, the face of the sign-plate may be provided with a protective coating of lacquer, either before or after making the printed impression, to prevent tarnishing of the metal. 100

The sign-plate after being printed is subjected to the action of embossing dies (see Fig. 4) for raising the unprinted portions 20 of the sign-plate, which are between the printed surfaces 16, above the printed surfaces, in imitation of the difference in height of the non-corroded and corroded portions of a genuine etched plate. The embossing dies comprise a raised die 21, preferably formed of a softer metal than the usual 105 steel embossing dies, such as zinc for example, and a coacting sunken die 22, prof-

erably formed of a material somewhat yieldable under pressure.

The die face 23 of the raised die, is exemplified as formed with raised portions 24 conforming to the portions of the sign-plate which are to appear in relief, and preferably having flat outer surfaces 25. These raised portions of the die-face are preferably formed slightly scant of the areas of 10 the unprinted portions 20 of the sign-plate, whereby the unprinted surfaces may be raised in relief by the raised die, without the liability of also raising parts of the printed surfaces 16 at the edges of the relief surfaces.

The sunken die is preferably formed by making an impression of the raised die in the surface of a layer of plastic material. As an exemplification, the sunken die is 20 instanced as formed by coating the upper surface of a flexible cushioning backing, such as a sheet of paper 27 which is placed upon the base of a molding press, with a plastic composition 28, instanced as a composition 25 having a putty base, and making an impression in the plastic composition by the raised die secured to the head of the molding press. A cushioned sunken die, somewhat yieldable under pressure, and having a matrix 30 complementary to the die face of the raised die, including flat bottom surfaces 29 in the depressions 30 of the matrix, is thus formed.

The sunken die is secured upon the platen 32 of an embossing press, and the sign-plate to be embossed is placed face down upon the sunken die with the unprinted portions of the sign-plate in registry with the depressions 30 in the matrix of the sunken die. 40 The raised die, secured to the head 33 of the embossing press, is then impressed into the backing of the sheet-metal sign-plate to force the metal of the facing of the sign-plate into the depressions of the sunken die. 45 A shearing action between the complementary lateral walls of the embossing dies will be prevented by the plastic material of the sunken die spreading slightly when under pressure, to accommodate the thickness of 50 the metal of the sign-plate between the coacting walls of the dies.

The comparatively thin, metal backing of the sign-plate is readily impressed and shaped by the raised die, as shown at 34, 55 without bending or buckling the adjacent portions of the sign-plate which are not impressed. The facing of the sheet-metal plate, being of a more tenacious and ductile metal, is readily bent and drawn out as 60 shown at 35, to conform to the contour of the matrix formed by the sunken die, and at the same time forms a binder for the less tractable backing layer of the metallic plate.

65 Sufficient pressure is exerted through the

raised die against the backing of the sign-plate, to force the metal of the facing of the plate against the plane bottom surfaces 29 of the depressions in the sunken die, so that flat surfaces 36 may be formed upon 70 the raised unprinted portions 20 of the surface of the sign-plate.

The embossing dies, having a certain amount of flexibility or pliancy, due to the use of one of the softer metals for the raised 75 die, and to the formation of the sunken die with a cushioning backing and of a yieldable, plastic, material, the dies will yield slightly when under pressure, so that the portions of the sheet-metal sign-plate to be 80 embossed may be raised to an appreciable height, without the liability of tearing the metal or cracking the ink upon the intaglio surfaces of the sign-plate at the edges of the surfaces which are in relief.

85

When the embossing of the sign-plate has been accomplished, the edges of the plate are preferably reversely bent, as shown at 38 (see Fig. 6), and the marginal portions of the plate may be beveled as shown at 39, by 90 any well-known mechanism. A backing-sheet 40 may be secured to the rear of the sign-plate for providing a neat and finished appearance.

Having thus fully described our invention, what we claim as new and desire to secure by Letters Patent, is:

1. The method of forming a sign plate which consists in printing a portion of the surface of a ductile metallic plate with a 100 heavy viscid ink, and embossing the unprinted portion of said plate so as to make said printed portion appear to be depressed with relation to said unprinted portion in imitation of the corroding effect of an acid 105 etching.

2. The method of forming a sign plate which consists in providing a ductile metal plate with a less tractable backing, printing a portion of the surface of said ductile 110 metal plate with a heavy viscid ink, embossing the unprinted portion of said plate while said ductile metal plate and less tractable backing are superposed and by means of a die and matrix, both of which are of 115 yieldable material, the material of said matrix being more yieldable than the material of said die, so as to make said printed portion appear depressed with relation to said unprinted portion, in imitation of the corroding effect of an acid 120 etching.

3. The method of forming a sign plate which consists in providing a ductile metal plate with a less tractable backing, printing a portion of the surface of said ductile 125 metal plate with a heavy viscid ink, embossing the unprinted portion of said plate with a die having less width than the width of said unprinted portion for preventing the raising of any of said printed portions to 130

the height of said unprinted portion and doing said embossing while said ductile metal plate and said less tractable backing are superposed, and by means of said die and a 5 matrix, both said die and said matrix being of yieldable material, the material of said matrix being more yieldable than the material of said die, so as to make said printed portion appear depressed with relation to said unprinted portion in imitation of the corroding effect of acid etching.

4. As an article of manufacture, a sign plate comprising a ductile metal plate and a less tractable backing therefor superposed, 15 said ductile metal plate and said less tract-

able packing having coinciding intaglio portions and coinciding cameo portions formed therein, said intaglio portions being printed with a viscid ink and said cameo portions standing out in relief, all in imitation of the 20 corroded and relief portions of an etched plate.

In testimony whereof we have hereunto signed our names in the presence of two subscribing witnesses.

EARL JAMES KIRKER.

THEODORE WILLIAM OLGES.
